(57) **CLAIM**

The ornamental design for a cart, as shown and described.

DESCRIPTION

FIG. 1 is a front, bottom and right-side perspective view of the cart showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is an enlarged top plan view thereof;

FIG. 7 is an enlarged bottom plan view thereof;

FIG. 8 is a rear, top and left-side perspective view thereof;

FIG. 9 is an enlarged view, of circled portion 9, of FIG. 1,

thereof; and,

FIG. 10 is an enlarged view, of circled portion 10, of FIG. 2, thereof.

The broken lines throughout the drawing figures depict portions of the cart that form no part of the claimed design. The dot-dash broken lines depict the boundaries of the FIGS. 1, 2, 9 and 10 enlargement that forms no part of the claimed design.

1 Claim, 10 Drawing Sheets
